Primary Examiner — Keli L Hill*Assistant Examiner* — Karra S Johnson(74) *Attorney, Agent, or Firm* — B. Craig Killough; Barnwell Whaley Patterson & Helms(57) **CLAIM**

The ornamental design for an audio speaker, substantially as shown and described.

DESCRIPTION

FIG. 1 is a front, top left hand perspective side of an audio speaker embodying our new design;

FIG. 2 is front elevation view of the audio speaker of FIG. 1;

FIG. 3 is rear elevation view of the audio speaker of FIG. 1; FIG. 4 is a top plan view of the audio speaker of FIG. 1; FIG. 5 is a bottom plan view of the audio speaker of FIG. 1; FIG. 6 is left side elevation view of the audio speaker of FIG. 1; and,

FIG. 7 is right side elevation view of the audio speaker of FIG. 1.

Broken lines are included for the purpose of showing unclaimed portions of the audio speaker.

1 Claim, 6 Drawing Sheets(56)
